DESIGN FOR AN ARM FOR LAMP FIXTURES

August O. Elting, Chicago, Ill.

Application January 2, 1940, Serial No. 89,257

Term of patent 3½ years

To all whom it may concern:

Be it known that I, August O. Elting, a citizen of the United States, residing at Chicago, in the county of Cook and State of Illinois, have invented a new, original, and ornamental Design for an Arm for Lamp Fixtures, of which the following is a specification, reference being had to the accompanying drawing, forming a part thereof, in which—

Fig. 1 is a plan view of the arm for lamp fixtures, showing my new design.

Fig. 2 is a side elevational view.

Fig. 3 is an inverted plan view.

Fig. 4 is an end elevational view thereof.

I claim:

The ornamental design for an arm for lamp fixtures, as shown.

AUGUST O. ELTING.
